(57) **CLAIM**

The ornamental design for a decorative furniture freezer, as shown and described.

DESCRIPTION

FIG. 1 is a front isometric view for a decorative furniture freezer with the lid shown in a closed position;

FIG. 2 is an enlarged upper left front fragmented isometric view thereof;

FIG. 3 is an enlarged upper right front fragmented isometric view thereof;

FIG. 4 is an enlarged left door isometric view thereof;

FIG. 5 is an enlarged right door isometric view thereof;

FIG. 6 is an enlarged lower front fragmented isometric view thereof;

FIG. 7 is a front elevational view of FIG. 1;

FIG. 8 is an enlarged front elevational view of FIG. 2;

FIG. 9 is an enlarged front elevational view of FIG. 3;

FIG. 10 is an enlarged front elevational view of FIG. 4;

FIG. 11 is an enlarged front elevational view of FIG. 5;

FIG. 12 is an enlarged front elevational view of FIG. 6;

FIG. 13 is a rear isometric view of FIG. 1;

FIG. 14 is a rear elevational view of FIG. 13;

FIG. 15 is an enlarged right side elevational view of FIG. 1;

FIG. 16 is an enlarged top plan view of FIG. 1;

FIG. 17 is an enlarged bottom plan view of FIG. 1;

FIG. 18 is a front isometric view for a decorative furniture freezer with the lid shown in an open position;

FIG. 19 is an enlarged isometric view of the lid of FIG. 18;

FIG. 20 is a front elevational view of FIG. 18;

FIG. 21 is a right side view of FIG. 20; and,

FIG. 22 is a top plan view of FIG. 18.

The broken line showing is included for the purpose of illustrating and forms no part of the claimed design.
